UNITED STATES PATENT OFFICE.

WALTER OSTHOFF, OF BARMEN, GERMANY.

PROCESS AND APPARATUS FOR SINGEING TEXTILE GOODS.

Application filed May 4, 1928, Serial No. 275,008, and in Germany February 22, 1928.

This invention relates to a process for singeing textile goods, and the invention consists in employing electric sparks or arcs for this purpose. The process can advantageously be carried out by causing a large number of continuous sparks produced by a high voltage to act on the goods, which sparks, in conjunction with the flame formation which occurs, effect the singeing 10 of the fibres.

If, for example, yarns have to be singed, a burner is advantageously employed in which the electrodes between which the formation of sparks takes place are separated from one another by some millimetres. The thread to be singed is drawn through the resulting spark-gap. The electrodes can either be arranged in pairs opposite one another or a plurality can be arranged radially 20 around the thread. Further, a plurality of electrodes can also be arranged one after another in the longitudinal direction of the goods to be singed.

The current can either be supplied to the 25 electrodes by connecting the one to the negative and the other to the positive pole of the source of the current, or the singeing can be carried out by heavily moistening the yarn before passing it into the burner so that the 30 wet thread to be singed forms one of the poles and acts, for example, as the earth conductor, while the electrodes opposite the thread are connected to the other pole. The formation of sparks by high voltage then 35 takes place between the electrodes and the wet thread to be singed.

The singeing of fabrics can, in accordance with the invention, obviously be effected in the same manner. Thus, for example, one pole may consist of a metal plate 40 over which the fabric is drawn while a holder with a large number of electrodes (for example, wires or needles) is arranged at the other side of the fabric at a distance 45 of some millimetres so that the spark from each wire must pass right through the fabric to the metal plate, which serves as a guide for the fabric.

When the goods to be singed by this process 50 are treated in a dry state the danger exists that they will be scorched or burnt by the sparks penetrating the fabric, that is to say, the body of the fabric itself will be

burnt. This method of singeing, therefore, cannot be employed with equal advantage 55 for all kinds of goods. In order to eliminate this danger, the process can, in accordance with the invention, advantageously be carried out by previously moistening the fabric. The result of this is that the spark can no 60 longer pass right through the fabric because its path is ended by the moisture in the fabric, i. e. by the water carried along by the fabric.

When carrying this process into practical 65 effect, the goods can advantageously be conducted over a roller which rotates in a water bath, so that the fabric is moistened on the side which travels on the roller, to which one pole, preferably the earth-conductor, is 70 connected.

Another advantageous method of carrying out the new singeing process consists in moistening the fabric so heavily before passing it into the spark-gap that it is itself able 75 to act as one of the poles, for example the earth-conductor. It is possible in this case to pass the fabric between a large number of oppositely situated electrodes and to cause the high voltage sparks to spring out 80 from the electrodes on both sides on to the wet fabric (earth conductor) passing between them. In this way the fabric is simultaneously singed on both sides.

Various forms of apparatus which can 85 advantageously be employed for carrying out the process are illustrated diagrammatically by way of example in the drawings, in which Fig. 1 is a vertical section of one form of apparatus having a plane guide 90 track for the goods to be singed, in combination with the pertaining electrical apparatus.

Fig. 2 is a vertical cross-section of a form of apparatus having a cylindrical guide 95 track and means for moistening the goods to be singed.

Fig. 3 is a plan of the electrode plate of the apparatus in accordance with Figs. 1 and 2.

Fig. 4 is an apparatus for singeing both sides of the fabric.

Fig. 5 is an apparatus having electrode plates arranged on both sides of the fabric but displaced from one another in the longitudinal direction.

Fig. 6 is a cross-section on the line 6—6 of Fig. 5.

Figs. 7 and 8 are apparatus for singeing yarns or threads in cross-section and in longitudinal section respectively, and

Figs. 9 and 10 are cross-section and plan respectively of a singeing apparatus having a spark-gap parallel to the path of the fabric.

Referring now to the constructional example illustrated in Fig. 1 of the drawings, 1 is the fabric to be singed and 2 a flat, hollow block of metal which serves as a support and also as a guide for the fabric and also further forms one pole of the spark-gap. Above the fabric 1 there is a second metal plate 3 which is provided at regular distances with points 4—4^x directed towards the fabric. These points 4—4^x form the separate electrodes and end at a distance of some millimetres, for example at a distance of 4—5 mm., above the path of the fabric.

The two plates 2 and 3 are each connected to one of the two ends 7^a, 7^b of the high-voltage coil 7 of the transformer 8, of which the low-voltage coil 9 is fed through a circuit-breaker 10 from a battery of accumulators 11 or other suitable source of current. For regulating the strength of the current, a variable resistance 12 is connected in the low-voltage circuit.

The upper side of the guide-plate 2 for the fabric is provided with a large number of slits or holes 2^a, and a pipe 14 for the supply of compressed air, steam or other suitable fluid medium is connected to the hollow space 2^a. Further, the guide-plate 2 is also connected to an earth-conductor E in order to prevent its being at an un-permissibly high electric potential above that of the earth.

The mode of operation of the apparatus illustrated in Fig. 1 is in short as follows:

The lever of the circuit breaker 10 is set in rapid rotation. Then, every time it passes over from the lower half-circle of its path of contact, which half-circle is made of insulating material, to the upper half, the current from the battery 11 is connected across the low-voltage coil 9. When, on the other hand, the lever of the circuit breaker leaves the upper half of its path of contact, the current is again cut off. At every make and break of the current a powerful induced voltage is set up in the high-voltage coil 7 which causes sparks or arcs 5—5^x to pass across between the points of the electrodes 4—4^x and the guide-plate 2. The speed of rotation of the circuit-breaker can be so regulated that about 50—100 spark discharges occur per second. The strength of the sparks or arcs is regulated according to the kind of material to be singed at any time by means of the resistance 12 and also by selecting a suitable battery voltage, so that

only the fine upstanding fibres of the fabric are burnt, while the fabric itself is not attacked by the flames.

For assisting the desired singeing action, compressed air may in addition advantageously be blown in through the pipe 14, so that it penetrates the fabric through the openings 2^a—2^x in the direction of the spark-gap. By this means the fuzzy fibres to be singed off are forced out from the surface of the fabric into the spark-gap so that they will burn away more easily. On the other hand, the combustion gases, generated by the combustion of the fibres, are blown away by the current of air and the oxygen necessary for the combustion is at the same time supplied. Finally, a certain amount of cooling of the plates and the electrodes 4—4^x is thereby effected, and this may in some cases also be further increased by other means.

As a numerical example for illustrating the effectiveness of the apparatus, the following will serve:—

It is possible without difficulty to cause about 100 sparks to spring from a single electrode in one second. A fabric which is 100 cms. wide can be singed, for example, with a burner for carrying out this process in which about 200 electrodes in the form of needles are arranged in the longitudinal direction. In the transverse direction, i. e., in the direction of travel of the fabric, 50 such rows, preferably staggered relatively to one another and each having 200 electrodes in the forms of needles or wires, may be arranged. Therefore, the burner for singeing a fabric which is 100 cms. wide has about 10,000 electrodes. Since about 100 sparks per second can be discharged without difficulty from one electrode, therefore for singeing this 100 cm. width of fabric as many as one million sparks spring onto the fabric per second. As the temperature of a single spark is extraordinarily high and, for example, far exceeds the melting point of all metals, there is formed along the singeing zone a single unbroken sea of flame of the highest temperature and in measurement about 100 cms. in length and 25 cms. wide. In consequence of the high temperature produced in the form of very numerous and very small micro-flames the fibres adhering to the goods are singed off without leaving any remains. The expenditure of energy in comparison with the effect produced is therefore very small and exceeds anything that has hitherto been obtained in this field of work.

The constructional example, illustrated in Fig. 2 differs from that of Fig. 1 essentially in that a rotating roller 2^a, which dips into a liquid container 2^b is used as a guide for the goods. This roller may suitably be made of ceramic material or other acid re-

sisting material, since if guide bodies of metal or the like be employed there is a danger that the metal will be attacked owing to the resulting formation of sparks and ozone and the high temperatures occurring, as well as owing to the influence of the moisture. Further, in some cases the goods themselves could be unfavourably affected by the metallic oxide. All these drawbacks are avoided by employing an acid resisting guide body, in which case the conduction of current takes place essentially through the liquid. As has been proved by experiment, the liquid has no effect whatever on the goods, but on the contrary quite a number of considerable advantages are gained by this moistening treatment, which are explained in greater detail in connection with the two following constructional examples.

In the constructional example according to Fig. 4 two electrode plates 3^a and 3^b are arranged one on either side of the fabric 1 to be singed. The fabric is conducted by a roller 2^e through a liquid container 2^f , which is itself connected to earth E and to one pole of the high-voltage coil 7.

The method of operation of the apparatus according to Fig. 4 is as follows:—

The fabric, on passing through the container 2^f is heavily moistened and thereby made conductive. The liquid may be ordinary water, to which in some cases may be added suitable salts or acids in order to increase its electrical conductivity. The fabric which has in this manner been made a good conductor and is connected to one pole of the coil 7 is then passed between the two electrode plates 3^a and 3^b . As the plates are connected to the other pole of the coil 7 a strong formation of sparks takes place simultaneously on both sides of the fabric as it passes between the electrodes, so that the fabric is singed on both sides at the same time, that is to say the singeing is finished in a single operation.

The heavy moistening of the fabric employed in this process has, as already indicated, the great advantage that only the upstanding fibres are burnt off, whilst the fabric itself is otherwise kept cool by the moisture and protected from being burnt.

In consequence, the danger of making the goods delicate and brittle owing to the effect of too great heat, as may happen with plate and flame singeing, is no longer present. The high temperature of the singeing spark is preeminently suitable for quickly removing the fibres adhering to the goods without leaving any remains, notwithstanding the presence of moisture.

The electrical singeing of fabric in a moist condition which has just been described has however other considerable advantages. Thus, for example, the high voltage sparks which are produced and shoot out in enor-

mous numbers simultaneously give rise to a strong formation of ozone which has a bleaching effect on the damp fabric. The bleaching process is thereby aided to a quite considerable extent, so that here again a new technical effect is involved within the bounds of the singeing process.

A further and very important advantage of the new singeing process is that the singeing process need no longer precede the bleaching process and that a previous drying of the goods is no longer necessary. The goods can on the contrary be dressed and bleached in the unsinged condition and can then be singed while still in the wet state, as they come from the bleaching, in the washing machine, or before the moistening calenders or in other suitable manner during an otherwise necessary process, so that a separate process of operation and corresponding loss of time is saved. Since the fabric is singed in accordance with the present process most advantageously after the bleaching process has been completed, the enormous advantage is with certainty obtained that the fabric is maintained faultlessly singed (free from fibres) until it is finished and that, as occurs with the previous singeing processes, new fibres do not again appear in the subsequent treatment and so impair the appearance of the goods.

The form of the apparatus in accordance with Figs. 5 and 6 differs from that of Fig. 4 essentially in that the two electrode plates 3^c and 3^d , which are arranged on different sides of the fabric 1 but one behind the other in the direction of travel, and that they are connected to different poles of the high voltage coil 7, while the fabric is heavily moistened as before and is in electrical connection with the earth conductor E.

Owing to the arrangement of the two electrode plates 3^c and 3^d connected to different poles the further special effect is obtained, as may be seen from Fig. 6, that the passage of sparks only takes place from those needles on the electrode plates which lie opposite a portion of the fabric, while those electrode needles which do not lie opposite a portion of the fabric remain out of action. In this way therefore the result is obtained that the spark formation automatically adapts itself to the width of the fabric being singed at any time.

A similar automatic regulation to the width of the fabric may be present also in the constructional example in accordance with Fig. 4 and obtained in that form by connecting the two electrode plates 3^a and 3^b to the same pole. The passage of sparks therefore only occurs from those needles located in that portion of the singeing zone within the range of the width of the fabric, as is illustrated in Fig. 6, by the full and dotted lines. Also when singeing with a

nonconducting roller in accordance with Fig. 2 an automatic adjustment of the spark formation to the width of the goods can be obtained. For this purpose it is only necessary to arrange the liquid bath 2^b in front of the roller 2^a instead of below it, so that the goods are moistened before they make contact with the roller, while the roller itself is wetted by the wet goods and only to a corresponding width, the rest of the roller remaining dry.

In Figs. 7 and 8 an apparatus for singeing yarns is illustrated diagrammatically. The electrode points 4^y—4^z are so arranged in two opposite arcuate electrode walls 2^g and 3^g that they point radially to the centre and are separated from one another by some millimetres corresponding to the spark-gap to be employed. The thread 1^b to be singed is passed through the centre surrounded by the numerous electrodes and since the sparks spring around it from all sides, the fibres present round the entire periphery of the thread are burnt away without leaving any remains.

In Figs. 9 and 10 a further constructional embodiment of the invention is illustrated, in which the electrodes 2^h, 3^h are arranged on one and the same side of the fabric and in such manner as to dispose the spark zone parallel to the path of travel of the fabric. In this form of apparatus for carrying out the process the exposure of the goods to the penetrating power of the spark is avoided, and the fabric may be moved at slow speed and less care is necessary in order to prevent possible burning of the fabric.

The invention is not of course limited to the constructional examples illustrated, but other forms of construction are possible. For example, instead of needles and wires, any other suitable kind of electrodes may be employed. They are however always so arranged that a large number of sparks can be formed between the electrodes and the goods to be singed or between the electrodes themselves. Further, the fabric instead of being passed horizontally between the electrodes could in many cases also pass in a vertical direction, for example, from below upwards.

Claims:

1. The process of singeing textile goods, which consists in subjecting the surface of the goods to be singed to the action of a singeing flame formed by electric sparks.

2. The process of singeing textile goods, which consists in moistening the goods to

be singed and subjecting the moistened goods to the action of a singeing flame formed by electronic emission.

3. The process of singeing textile goods, which consists in subjecting one side of the goods to the singeing action of a singeing flame formed by electric sparks, and simultaneously subjecting the other side of the goods to the action of a fluid under pressure.

4. The process of singeing textile goods, which consists in subjecting the goods to the singeing action of singeing flames formed by electronic emission, and simultaneously subjecting the other side of the goods to the action of an oxygen containing fluid under pressure.

5. The process of singeing textile goods which consists in moistening the goods so as to render the goods electrically conductive, placing one side of the goods at ground potential, and subjecting the other side of the goods to the action of a singeing flame produced by electric sparks.

6. An apparatus for singeing textile goods, comprising goods supporting means, and means operative for producing by electronic emission a singeing flame to act upon the goods.

7. An apparatus for singeing textile goods comprising supporting and guiding means for the goods, means for moistening the goods, and means for producing a singeing flame formed of electric sparks to act upon the goods.

8. An apparatus for singeing textile goods comprising supporting and guiding means for the goods, means for dampening the goods, means for placing one side of the goods at ground potential, and means for producing a singeing flame formed of electric sparks for action upon the goods.

9. An apparatus for singeing textile goods comprising supporting and guiding means for the goods, means for producing a singeing flame formed of electric sparks to act upon a side of the goods, and means for subjecting the opposite end of the goods to the action of an oxygen containing fluid under pressure.

10. An apparatus for singeing textile goods comprising supporting and guiding means for the goods, means for producing singeing flames formed of electric sparks to act upon the surface of the goods, and means for subjecting the opposite surface of the goods to the pressure of a pressure fluid.

In testimony whereof I affix my signature.

WALTER OSTHOFF.
